DRAIN-PIPE GUIDE.

Application filed May 13, 1927. Serial No. 191,107.

Our invention relates to a combined conduit and guide more especially intended for the drain pipes of a locomotive; the invention having for its object the provision of a 5 device whereby the drain pipes of the water columns, water glasses and gauge cocks, as well as other drains located in the cab of a locomotive, may terminate above the deck of the cab and at the same time be rigidly held 10 in proper position relative to the drain opening or openings in the deck or floor of the cab and enable proper visibility of the drain or leakage from the respective devices with which the drain pipes are connected.

15 The invention also has for its object the provision of a construction whereby a fixed minimum indicating space will be maintained at the lower end of the drain pipe or pipes while at the same time preventing 20 foreign objects or material of size larger than the drain openings in the cab floor becoming lodged in said opening and causing a stoppage.

The invention also has for its object the 25 provision of a simple construction which may be readily applied to the drain conduits or pipes of a locomotive at present in use and which may be as quickly removed should occasion require.

30 The above enumerated objects and the advantages inherent in the construction will all be readily comprehended from the detailed description of the drawing, wherein-

Figure 1 is an elevation of our improved 35 device shown applied to the lower end of a conduit and its application to the deck of a locomotive cab of which a portion, as well as a portion of the rear boiler head, is shown in section.

40 Figure 2 is a front elevation thereof.

Figure 3 is a vertical sectional view.

Figure 4 is a cross sectional view taken on the line 4-4 of Figure 2 looking in the direction of the arrows.

45 Figure 5 is a detail perspective view of the pipe clamp member.

Our improved device is shown as especially intended for use in connection with the drain pipes or conduits of the water 50 columns, water gauges and gauge cocks, located in the cab of the locomotive whereby safe operation of the various steam gene-

rators or devices will be ensured, while at the same time complying with the recommendations of the American Railway Association and the Interstate Commerce Commission relative to the termination of the drain pipes or conduits a predetermined distance above the deck or floor of the cab of the locomotive, to-wit substantially an 55 inch thereabove; the condensate or steam discharging through a hole in the deck or floor of the cab of dimensions slightly larger than the outside diameter of the pipes or conduits. The object in having the pipes or conduits terminate above the deck or floor 60 is to enable visibility by the engine crew of the operation of the respective drain pipe and thus to determine the nature of the discharge or extent of any leakage that may be taking place through the respective pipes or conduits. In complying with the above 65 mentioned recommendation, considerable difficulty has been encountered in keeping the pipes or conduits aligned with the openings in the deck or floor of the cab because of excessive vibrations and frequent contact with the conduits or pipes. As a result of the non-alignment of the lower free ends of the pipes with the holes in the cab-deck, 70 water and steam has blown over or been discharged onto the deck instead of through the drain opening in the deck or floor and consequently has caused the cab to be filled 75 with steam.

Our device is intended to carry out the recommendations above referred to and at the same time provide for the safety and comfort of the engine crew. In the particular exemplification as disclosed in the drawing, 10 represents a portion of the back boiler head provided with the usual lagging 80 11, while a portion of the deck or floor of the cab is shown at 12. The lower end of a drain pipe or conduit is shown at 13, which 85 may lead from a water glass, gauge cock, or other hot water and steam device located in the cab of the locomotive. The conduit terminates at a predetermined distance above the deck of the cab (say one inch above the floor in compliance with the recommendations) with its lower end disposed in vertical alignment with the axis of an opening 14 through the deck or floor of the 90 95 100

cab; the opening being preferably slightly larger than the outside diameter of the pipe or conduit 13.

Our device comprises a conduit or thimble 5 portion 15 adapted to extend into the opening 14 in the deck 12 of the cab of the locomotive and is provided externally at an intermediate point with an annular flange 16 adapted to rest on the deck of the cab. The 10 upper end of the thimble or conduit portion 15 of the device is shown preferably flared outwardly as shown at 17 and this flared perimeter is provided with the integral upstanding lugs or prongs 18 spaced circumferentially apart along the front side of the device; the lugs being preferably a sufficient distance apart to provide suitable large openings therebetween. The rear side, namely the side disposed toward the boiler, 15 is provided with an integral upstanding arm 19 of length somewhat greater than the height of the lugs or prongs 18. This arm 19 terminates in the laterally extending arcuate pipe engaging head or portion 20 20 having the concaved inner face conforming with and adapted to receive the drain conduit or pipe 13 as more clearly shown in Figures 3 and 4. The head portion 20 is disposed vertically in a plane defined or 25 circumscribed by the thimble portion 15. The head portion 20 is provided with the outwardly extending lobe 21 and substantially diametrically opposite thereto with the laterally disposed bifurcations 22, 22. 30 The bifurcations 22 are disposed one above the other and preferably curve or bend rearwardly so as to provide the socket forming portion 23 which is adapted to receive the vertically and oppositely disposed trunnions 24 formed on one end of a clamp 35 member 25. The clamp member 25 is formed to partially fit about the drain conduit or pipe, with the end opposite to that having the trunnions 24, provided with a lobe 26 adapted to extend substantially parallel 40 with lobe 21 formed on the head 20 of arm 19. The end of clamp member 25, which is provided with trunnions 24, namely the portion 27 adjacent to the trunnions, is 45 of vertical width somewhat less than the distance between the bifurcations 22, 22 to permit the neck portion 27 of clamp 25 to fit therebetween while the trunnions 24 are disposed in the sockets 23 on the rear 50 side of bifurcations 22 when the clamp member 25 is disposed about the forward side of the drain pipe. The lobes 21 and 26 are apertured to receive suitable fastening means shown in the nature of a suitable bolt 28 55 with its nut 29; the aperture in the lobe 21 being preferably non-circular in configuration to receive the squared portion of the bolt and prevent rotation thereof.

The main body or thimble portion 15 is 60 preferably internally formed to provide a

passage-way therethrough increasing in diameter toward the lower end and slightly flared at the upper end to receive the drain from pipe 13; the flared construction, as is apparent, will prevent stoppage of the conduit portion by freezing.

The upstanding lugs or prongs 18 are merely of a height sufficient to prevent foreign objects entering or rolling into the upper end of the conduit portion while at the 75 same time not interfering with proper visibility but permitting the crew to discern the nature or condition of the fluid issuing from the drain conduit or pipe 13 which terminates a distance above the tops of the 80 prongs or lugs 18 as shown.

With our improved device a positive aligning of the ends of the drain pipes or conduits is not only obtained, but such aligned condition maintained by the firm gripping relation existing between the device and the lower end of the drain pipe; thus ensuring safe operation of the steam generators or devices, while providing a fixed minimum opening or indicating space 90 in compliance with the requirements of the Interstate Commerce Commission heretofore referred to.

It will be understood, of course, that the size or inside diameter of the device may be 95 varied in keeping with the drain pipes or conduits in connection with which it is to be employed. With the trunnions 24 arranged in interlocking relation with the bifurcations 22 and the nut 29 firmly screwed up on bolt 28, it is apparent that the device will be firmly clamped to the drain pipe thus 100 constantly maintaining the latter in proper position relative to the drain opening in the cab deck or floor. The construction of our improved guide is such that it can be quickly applied to the drain pipes and as readily removed when occasion requires by simply unscrewing nut 29 and removing bolt 28 from the apertures in lobes 21 and 26, which will 105 allow the clamp member to swing toward the trunnions 24 thereby effecting their release from the bifurcations 22.

The conduit portion of the device in the specific embodiment shown is extended 110 above the annular flange or shoulder 16 in order to have the top orifice of said portion and the sight openings or space disposed above the floor or the cab deck so as to prevent coal or other material rolling or falling 115 into the conduit portion.

In order that the bottom of the drain pipe 13 may remain in predetermined spaced relation with the upper end of the main body of the conduit, namely in spaced relation with the bottom of the sight opening, in keeping with requirements, the arm 19 is shown provided on its inner side with a projection 30,—which may be in the nature 120 of a reinforcing web as shown in Figure 125 130

3.—extending into alignment with the drain pipe 13. The projection is shown recessed at its top to provide a shoulder or seat 31, for the lower end of the drain pipe 13.

5. This shoulder is formed at the desired or required distance from the upper perimeter 17 of the device. It is apparent, therefore, that the lower end of the drain pipe will be constantly held a predetermined distance 10 from the lower end of the sight opening so that proper visibility is at all times provided.

Although the device is especially intended for use on the deck of a locomotive cab, it is 15 obvious that it is equally well adapted for other uses or in connection with boilers employed for other purposes and that the invention may have expression in somewhat different form. The embodiment of the invention as shown in the drawing has been 20 described in terms employed merely as terms of description and not as terms of limitation, as modifications in certain respects may be made without, however, departing from the spirit of our invention.

25 What we claim is:

1. A device of the character described, comprising a thimble portion, an upstanding arm integral with one side of the thimble portion, the upper end of said arm terminating in a pipe engaging portion, and a pipe clamping member, the ends whereof are adapted to be secured to the pipe engaging portion of said arm for clamping the pipe.

35 2. A device of the character described, comprising a conduit portion, the perimeter at one side being provided with an upstanding arm terminating at top in a pipe engaging portion, one side of said portion being bifurcated while the other side has an opening, and a pipe clamping member, one end whereof has oppositely disposed portions adapted to interlock with the bifurcations of the arm, while the other end has an opening 40 adapted to register with the opening in the arm and to receive a fastening bolt.

3. A device of the character described, comprising a thimble portion provided with a floor engaging flange, the upper end of 50 said portion being formed to provide spaced upstanding lugs, a vertical arm extending above the tops of the lugs and terminating in a pipe engaging head, one side whereof is transversely slotted while the other side has a bolt-receiving aperture, and a pipe clamp, one end whereof is apertured and adapted to extend parallel with the apertured side of the head while the other end is formed to interlock with the slotted side of said head.

60 4. A device of the character described, comprising a thimble portion internally flared toward one end, the upper end of the thimble portion having spaced upstanding lugs, one side of the thimble portion having 65 a vertical arm extending above the tops of

the lugs and terminating in a pipe engaging head having outwardly extending sides, and a pipe clamp, one end whereof is adapted to have interlocking engagement with one side of said head, and means whereby the other end is removably secured to the other side of said head.

5. A device of the character described, comprising a thimble portion having upstanding lugs spaced apart circumferentially, 70 an arm extending upwardly from one side of the thimble portion and terminating in a pipe engaging head having laterally disposed lobes on opposite sides, one of said lobes being slotted transversely from the outer end, a pipe clamp, one end whereof is provided with vertically extending trunnions adapted to interlock with said slotted lobe, and means whereby the other end of said clamp and the other lobe of said head 75 are removably secured together.

6. A device of the character described, comprising a conduit portion and a drain pipe clamping portion, the forward side of the conduit portion below the drain pipe 80 clamping portion being formed to permit visibility of the interior of the device, the pipe clamping portion involving adjustable means for effecting clamping relation with the drain pipe.

95 7. A device of the character described comprising a conduit portion and a drain pipe clamping portion disposed above the conduit portion, the device intermediate of said clamping portion and conduit portion 100 being provided with a drain pipe abutting shoulder and being cut away except at the rear side of the device to provide a sight opening at the front and sides of the device.

8. A device of the character described 105 comprising a conduit portion adapted to extend into and seat around a hole in a floor, said portion above its floor engaging surface being formed to permit visibility of its interior, a drain pipe engaging portion at the upper end of the device, and means for controlling the spaced relation between the lower end of the drain pipe and said floor engaging surface.

110 9. A device of the character described 115 comprising a conduit portion provided at an intermediate point with a floor engaging portion and formed thereabove with a sight opening, and a drain pipe engaging portion at the upper end of the device provided with a drain pipe abutting shoulder.

120 10. A device of the character described 125 comprising a thimble portion provided at an intermediate point with a floor engaging shoulder, an upstanding arm on one side of the thimble portion, said arm on its inner face having a projection on which the lower end of a pipe is adapted to rest, while the upper end of said arm terminates in a pipe engaging head having outwardly extending 130

wings on opposite sides, one of said wings being slotted transversely and curving rearwardly while the other wing is apertured, a pipe clamping member provided at one end with upwardly and downwardly extending portions adapted to interlock with the slotted wing of said head while the opposite end of said member is apertured and adapt-

ed to extend substantially parallel with the apertured wing of said head, and fastening means disposed through the apertures in said wing and said end of the clamping member. 10
